(57) **CLAIM**

I claim the ornamental design for a cue bridge, as shown and described.

DESCRIPTION

FIG. 1 is a perspective view of the cue bridge showing my new design

FIG. 2 is a front view thereof;

FIG. 3 is a side view thereof;

FIG. 4 is a top view thereof; and,

FIG. 5 is a perspective view thereof, shown the invention in environmental use.

The broken lines showing a ball, a pool cue, and a hand in FIG. 5 are for environmental purposes only and form no part of the claimed design.

1 Claim, 5 Drawing Sheets

FIG. 1

FIG. 2

FIG. 3

FIG. 4

FIG. 5
